UNITED STATES PATENT OFFICE.

PERCY W. STEPHENS, OF CHICAGO, ILLINOIS.

FUEL-RESERVOIR SYSTEM.

Application filed October 19, 1925. Serial No. 63,248.

This invention relates to improvements in fuel reserve systems, and more particularly to an attachment for use with fuel tanks of standard construction, and has for its principal object to provide a simple device of the character described, whereby a reserve supply means may be readily applied to a standard form of fuel outlet.

More specifically, my improved device is particularly designed for use with the supply tank of Ford automobiles, in which the outlet fitting on the tank comprises an L-shaped duct leading downwardly from the bottom of the tank and thence laterally to a threaded coupling, for connection with the fuel supply line. My invention contemplates the provision of a fuel reserve device comprising an auxiliary fitting, which may be attached to the standard form of outlet fitting described, without disturbing the correlated parts of the machine.

The invention may best be understood by reference to the accompanying drawings, in which

Figure 1 is a side view of a standard form of fuel tank and outlet fitting with one form of my improved fuel reserve device applied thereto.

Figure 2 is a sectional view of the device shown in Figure 1.

Figure 3 is a sectional view taken on line 3-3 of Fig. 1, illustrating the manner of operation of the device.

Figure 4 is a vertical section taken through the outlet fitting of the tank, and illustrating the method of attaching the device thereto.

Figures 5 and 6 are longitudinal and transverse sectional views respectively, of a modified form of my invention.

Figure 7 is another modified form of my invention shown in longitudinal section.

Figures 8 and 9 are transverse sectional views taken on line A-A of Fig. 7, but showing the valve means in different positions.

Referring to details of construction of the form shown in Figures 1, 3, and 4, 10 indicates a fuel supply tank having a standard outlet fitting 11 at the bottom and adjacent one side of said tank. Said fitting has a relatively short vertically disposed passage 14 communicating with a horizontally disposed passage 15 having its outer end tapped as at 16 for connection with a coupling for the usual fuel supply line. In the form

shown in Figs. 1 and 4 it will be understood that the usual coupling is removed from direct attachment with fitting 11, and my improved device is interposed between said fitting and said coupling, indicated at 17.

Referring now to my improved attachment, the same consists of a body member 20 having a threaded end 21 adapted to be screwed in the tapped portion 15 of the outlet fitting 11. Projecting from the threaded end, I provide a piece of tubing 22 so formed that it may be inserted through the passages 15 and 14 of the outlet fitting 11 before the threaded part 21 is connected with said outlet fitting. For this purpose the inner portion 23 of said tube is arranged at an angle of substantially 90° to the main part thereof, as shown. The extreme end of said tube is also preferably formed with a slight lateral bend as indicated at 23a, the purpose of which will be subsequently described.

The tube 22 extends through a chamber 24 in the body member 20 and has tight fitting engagement at both ends of said chamber, although having longitudinal and rotational movement relative to said body member. In the form shown, the tube has a plain fitting bearing at the inner end of the body member and passes through a gland 25 at the opposite end of said body member. As herein shown, this gland comprises a cap 26 threaded into said body member and having a coiled spring 27 extending longitudinally of the tube within the chamber 24, said spring 90 extending into the cap and being normally under tension to retain a packing ring 28, in place.

Means are provided for positively moving the tube 22 comprising a handle 30 secured at the outer end thereof in position to be readily manipulated by hand. In the form shown, this handle consists of a knurled button, whereby said tube may be either rotated or moved longitudinally in the body member as required. Said tube is provided with suitable apertures, such as holes 31-31, adjacent the central portion thereof within the chamber 24, the arrangement being such that the tube has communication through these apertures with the chamber 24, in all permissible positions of said tube when the device is in operation. The body member is provided with an outlet 35 communicating with the chamber 24. In the specific forms shown in Figures 2 and 3 this outlet is disposed at an angle to the body portion and

has a tapped outer end 29 adapted to receive the usual coupling device which ordinarily is connected directly to the standard outlet fitting 11. In practice, this outlet fitting 5 may be of any standard form, as, for instance, it may comprise either a sediment bulb or filter with a shut-off valve associated therewith, or it may consist of a plain coupling device attached to the upper end of a 10 fuel supply line.

The use and operation of my improved device above described is substantially as follows:

When the usual coupling connection is removed from the outlet fitting 11, my device 15 is applied by first inserting the bent end 23 of the tube 22 into the horizontally disposed passage 15 of the outlet fitting and then by twisting or turning the device, said tube may 20 be passed upwardly through the vertically disposed passage 14 into position to project above the bottom of the supply tank 10. It will be understood, however, that it is not practical to positively engage the threaded 25 portion 21 of my improved attachment with the tapped portion 16 of the outlet fitting until the tube 22 has been fully inserted by the turning or twisting of the entire attachment as just described. Consequently, I 30 provide for longitudinal movement of the tube with respect to the body member 20 so that after the tube is fully inserted, the body member may be slid along the tube into position to engage its thread 21 in the tapped 35 portion 16 of the fitting. The device may then be screwed into the fitting. It will be understood that the tube is maintained against rotation, and has very limited longitudinal movement as it is in place in the 40 outlet fitting 11, but the arrangement of the tube with its movable mounting in the body permits the body to be fully screwed into the fitting. After the device is fully coupled to the outlet fitting, the fuel supply line coupling is connected to the outlet 35 of the device in the usual manner.

In the operation of inserting the device, the 45 end 23 of the tube projecting into the tank is usually turned in the direction of screwing until it is stopped by the side walls of the passage 14. In order to set the apparatus for proper functioning after the device is fully inserted, this tube is rotated by means of the handle 30 in the reverse direction 50 so that the end portion 23 extends in a generally vertical position, so as to extend considerably above the bottom of the tank 10. In this position, it will be observed that the fuel in the tank can run through the tube 55 and be furnished to the vehicle motor only so long as the fuel level remains above the upper end of said tube. When the fuel level falls below the upper end of the tube, however, the motor will misfire or stop so as to 60 give warning that the fuel is getting low.

The operator may then manipulate the handle 30 of the tube by rotating it in a direction to move the inner end of the tube 23 downwardly toward the bottom of the tank. In the form shown, the bent portion 23^a of 70 said tube is provided so that the extreme end of the tube may lie on the bottom of the tank, and the adjacent portions of the tube may be substantially parallel with the bottom of the tank, when in lowered position. 75 The remaining fuel in the tank may then flow through the tube, thus forming in effect a reserve supply usually sufficient to permit replenishment before all of the fuel is exhausted.

Figure 5 shows a modified form of my invention in which the parts of the device are the same with the exception that a shut-off valve 40 is incorporated in the body member itself, this shut-off member being a simple 80 form of needle valve offset from the chamber 24 and communicating with an outlet 41 adapted to be connected directly to the fuel supply line.

Another modified form is shown in the Figures 7, 8, and 9, wherein the tube 22 passes through a conically shaped plug member 45 arranged coaxially therewith and engaging a valve seat 46. Said plug member has two lateral extending ports 47 and 48 90 adapted for selective communication with an outlet passage 35 formed in the valve seat as shown in details in Figures 7 and 8. The plug 45 is normally maintained in engagement with the valve seat by a coil spring 50 which also serves to keep the packing 28 in place in the gland 25. The usual handle 30 is provided at the outer end of the tube 22 for rotating the same and connection is also made between said tube and the plug member 95 for rotating the plug and in permitting limited longitudinal movement of the tube with respect to the plug as desired. In the form shown this means comprises a pin 51, arranged transversely of the tube 22 and projecting therefrom to move in a longitudinal slot 52 formed in said plug.

The arrangement is such that the port 47 registers with the aperture 49 when the fuel inlet tube is raised in an uppermost position in the fuel supply tank as shown in Figure 7. In the second position shown in Figure 8 neither ports are in registering position with the outlet 49 so that the plug acts as a shut off valve. In the third position shown in Figure 9, the second port 48 communicates with the outlet passage 49 when the inlet end of the tube is in its lowermost position in the supply tank as indicated in Figure 9. In this specific form therefore 115 it will be observed that the handle 30 not only controls the longitudinal and sliding movement of the tube, but also controls a shut off valve within the body member. It 120 will be understood, however, that in some 125 130

cases the longitudinal sliding movement of the tube may be dispensed with where it is not required on account of the shape of the outlet fitting to which the device is applied,

5 in which case the plug 45 may be mounted rigidly with the tube 22.

Although I have shown and described one form in which my invention may be embodied, it will be understood that many 10 changes in form and construction will occur to those skilled in the art without departing from the spirit and scope of my invention. I do not therefore wish to be understood as limiting myself to the construction shown 15 and described herein, excepting in so far as specifically defined in the appended claims.

I claim as my invention:

1. A reserve liquid control device comprising a tube having a part extending at an angle to the remainder thereof, a body member surrounding and having a rotatable and liquid tight fit with one of the parts of said tube said body member being provided with an outlet coupling having communication 25 with said tube within said body portion, and means for attaching said body member to an angular outlet of a tank with the angled part of said tube projecting thereinto.

2. A reserve liquid control device comprising a tube having a part extending at an angle to the remainder thereof, a body member providing a cylindrical liquid tight bearing for one of the parts of said tube on an axis extending longitudinally of the latter 35 and with the angled part of said tube free to rotate at the end of said body member, said body member having an outlet coupling communicating with said tube intermediate its ends, means for attaching said body member to a tank with the angled part of said tube projecting thereinto, and means extending from said body member for manually rotating said tubular member.

3. A reserve liquid control device comprising a tube having a part extending at an angle to the remainder thereof, a body member providing a cylindrical liquid tight bearing for an intermediate part of said tube and with the angled part of said tube free to rotate at the end of said body member, said body member having an outlet coupling communicating with said tube intermediate its ends, means for attaching said body member to a tank with the angled part of said 50 tube projecting therein, said tube extending through said body member and having means at the outer end for rotating the same in said body member.

4. A reserve liquid control device comprising a tube having a part extending at an angle to the remainder thereof, a body member surrounding and having a liquid tight fit with one of the parts of said tube but affording a rotatable and longitudinally slidable movement thereof, and threaded means

for attaching said body member to an angular outlet fitting on a tank with the angled part of said tube projecting through said fitting and into said tank.

5. A reserve liquid control device comprising a tube having a part extending at an angle to the remainder thereof, a body member surrounding and having a liquid tight fit with one of the parts of said tube but affording a rotatable and longitudinally slidable movement thereof, threaded means for attaching said body member to an angular outlet fitting on a tank with the angled part of said tube projecting through said fitting and into said tank, and means extending from said body member for controlling the movement of said tube. 70

6. A reserve liquid control device comprising a tube having a part extending at an angle to the remainder thereof, a body member surrounding and having a liquid tight fit with one of the parts of said tube but affording a rotatable and longitudinally slidable movement thereof, threaded means for attaching said body member to an angular outlet fitting on a tank with the angled part of said tube projecting through said fitting and into said tank, said tube extending through said body member and having means on the outer end thereof for controlling the movement thereof. 85

7. A reserve liquid control device comprising a tube having a part extending at an angle to the remainder thereof, a body member surrounding and having a rotatable and liquid tight fit with one of the parts of said tube, and means for attaching said body member to an L-shaped outlet fitting opening downwardly at the bottom of a tank, the angular part of said tube being bent laterally so that the extreme end thereof will lie along the bottom of the tank when moved to one position therein. 90

8. A reserve liquid control device comprising a tube having a part extending at an angle to the remainder thereof, a body member surrounding and having a liquid tight fit with one of the parts of said tube, but affording a rotatable and longitudinally slidable movement thereof, and means for attaching said body member to an angular outlet fitting on a tank with the angled part of said tube projecting through said fitting and into said tank. 100

9. A reserve liquid control device comprising a tube having a part extending at an angle to the remainder thereof, a body member surrounding and having rotatable and liquid tight fit with one of the parts of said tube, means for attaching said body member to an angular outlet fitting on a tank with the angled part of said tube projecting through said fitting and into said tank, and means extending from said body member for manually rotating said tubular 105

member into a plurality of positions with the inlet end of said tube at different heights and in another position to form a shut off valve.

- 5 10. A reserve liquid controlled device comprising a tube having a part extending in an angle to the remainder thereof, a body member surrounding and having a liquid tight fit with one of the parts of said tube 10 affording a rotatable longitudinal sliding movement thereof, a valve member rotatably mounted on said tube and having a plurality of ports therein, affording com-

munication from said tube to an outlet in said body member, common means extending from said body member for controlling the movement of said tube in said body member and the rotation of said valve member in said body member and means for attaching said body member to an angular fitting 20 on a tank with the angled part of said tube projecting through said fitting and into said tank.

Signed at Chicago, Ill., this 14th day of October 1925.

PERCY W. STEPHENS.
